Filed Apr. 20, 1962, Ser. No. 69,793

Term of patent 14 years
(Cl. D33—1)

FIGURE 1 is a perspective view of my new design for a room divider or the like;

FIGURE 2 is an enlarged side elevational view of FIGURE 1; and

FIGURE 3 is an enlarged fragmentary perspective view of the upper central portion of FIGURE 1.

The end not shown is like the end shown, and the back of the upper portion of the room divider or the like is open like the front and has a corresponding closed central portion which is plain.

The dominant features of my design reside in those portions shown in full lines wherein the room divider or the like comprises a framework of open shelving so arranged as to extend completely about a centrally located panel arrangement, and wherein each panel in the panel arrangement projects beyond the plane of the body portion of the room divider or the like, and each of the

panels in said group being defined by a groove extending about its respective periphery.

I claim:

The ornamental design for a room divider or the like, as shown and described.
